UNITED STATES PATENT OFFICE.

DELANO H. DUGAR, OF ELYRIA, OHIO.

EXPANSION-REAMER.

1,202,169.

Specification of Letters Patent. Patented Oct. 24, 1916.

Application filed August 10, 1915. Serial No. 44,701.

To all whom it may concern:

Be it known that I, DELANO H. DUGAR, a citizen of the United States of America, residing at Elyria, in the county of Lorain 5 and State of Ohio, have invented certain new and useful Improvements in Expansion-Reamers; and I hereby declare the following to be a full, clear, and exact description of the invention, such as will enable 10 others skilled in the art to which it pertains to make and use the same.

This invention relates to new and useful improvements in expansion reamers.

One object of this invention is to provide 15 new and improved means for supporting and connecting the body or blade carrying portion of the reamer with the shank portion so that the body portion will have a slight movement independent of the shank 20 transversely of the axis of the shank permitting the body portion to float with respect to the supporting spindle and thereby compensate for any eccentricity of the spindle.

25 A further object of this invention is to provide a new and improved driving connection between the shank and the body portion so that the strain will be equally distributed when the tool is being driven.

30 A further object of my invention is to provide new and simple means for mounting the cutting blades in the body which will permit delicate adjustment thereof and positive locking of the blades in position after 35 they have been adjusted.

40 My invention further consists in the features of construction and combination of parts hereinafter described in the specification, pointed out in the claims and illustrated in the accompanying drawings.

Again referring to the drawings, Figure 1 is a bottom plan of a reamer embodying my invention. Fig. 2 is a section on line 2—2, Fig. 1. Fig. 3 is a section on line 3—3, Fig. 45 2. Fig. 4 is a section on line 4—4, Fig. 2. Fig. 5 is a section on line 5—5, Fig. 4. Fig. 6 is a section on line 6—6, Fig. 2. Fig. 7 is a section on line 7—7, Fig. 2.

50 Like parts are identified by the same reference numerals throughout the several views, but it will be understood that the use of the words "upper," "vertical," "horizontal," "lower," etc., are used relatively with reference to the position of the parts 55 on the sheets of drawings as the reamer may be used in any position desired.

Again referring to the drawings, 10 represents the shank of my improved reamer which is adapted to fit into a socket in the end of the spindle *a* of a boring machine. 60 On the lower end of the shank 10 is formed an annular flange 11 in which are formed two diametrically opposite openings 12, and in said openings are secured pins 13 which extend down below the lower surface 65 of said flange 11. In the bottom face of said flange are formed four cavities or seats 14 in which are arranged plugs 15 of hardened steel. Small holes 16 are formed in the top surface of the flange 11 and communicate 70 with said cavities 14, the said holes being adapted to receive a tool for knocking out the plugs 15 when the exposed surfaces thereof become worn. At the center of the shank 10 is formed a bore 17 which extends 75 upwardly from the lower surface of the shank and the inner end of the bore is tapered or conical shaped as shown at 18.

The blade carrying portion of the reamer is exteriorly cylindrical in shape, but at its upper end the outer circumference thereof is reduced forming a neck portion 23 which is provided with an exterior screw thread. In the said neck portion 23 is formed a circular cavity or socket 24 and the wall of 80 the said cavity 24 is screw threaded adjacent to the upper end of said cavity. The circumference of the said cavity is slightly greater than the circumference of the flange 11 on the shank 10 so that when the said shank is inserted in said cavity the blade carrying portion can move or shift transversely of the axis of the shank portion, or, 85 as it is technically termed, can float on the shank portion. The part of the blade carrying portion below the neck portion, indicated by 25, will hereinafter be termed the body portion, and in said body portion is formed an annular cavity 26 which extends 90 upwardly from the bottom surface of the body portion. The diameter of said cavity 26 is increased a short distance from the lower end forming a shoulder 27, and the wall of the cavity below said shoulder is provided with a screw thread. The part of 95 the body portion which extends down centrally and forms the inner wall of said cavity 26, and which is indicated by 28, will hereinafter be termed the hub portion. The lower end of this hub portion is reduced in 100 diameter, as shown at 29, and is screw threaded. In the bottom wall of the cavity

105

110

24 in the neck portion are formed two openings 32 which are arranged diametrically opposite each other, and in said openings are secured pins 33, and when the shank and blade carrying portions are in their assembled position the said pins 33 extend in a vertical plane at a ring angle to the vertical plane of the pins 13 on the flange 11. In the upper surface of the bottom wall of said cavity 24 are also formed four cavities 35 in which are arranged plugs 36 of hardened steel, and the said plugs 36 in the assembled position of the shank and blade carrying portion are in line with each other and form bearing surfaces for ball bearings as will appear later. Within the said cavity is arranged a circular plate or disk 37 which is adapted to rest on the bottom wall of said cavity, and the diameter of this disk is less than the diameter of the cavity. In the said disk 37 are formed four U-shaped openings or slots 38 which extend inwardly from the perimeter of the disk and are spaced apart equal distances circumferentially, and when the reamer is assembled the two pins 33 will extend up through two diametrically opposite notches in said disk and the pins 13 will extend down through the other two diametrically opposite notches in said disk thereby forming an operative connection between the shank portion and the blade carrying portion. Rollers 39 are mounted in the sides of the pins 13 and 33 where said pins extend into the openings 38 in said disk 37 and form anti-friction rollers. These rollers are arranged at opposite sides of each pair of pins and project slightly beyond the peripheral surfaces of the pins so as to contact with the adjacent side walls of said openings 38. In the said disk 37 are also formed circular openings 40 which extend entirely through said disk and are in line with the hard steel plugs in the bottom wall of the cavity 24 and in the under surface of the flange 11. In said openings 40 are mounted balls 41 which are slightly larger in diameter than the thickness of said disk, and said balls 41 form roller bearings between the bottom of the cavity 24 and under surface of the flange 11. A locking ring 43 is screwed into the upper end of the cavity 24 above the flange 11, and the inner diameter of said ring is slightly greater than the diameter of the shank 10 leaving a clearance between the shank and the said ring. Any suitable packing 45 is arranged between the upper surface of said ring 43 and the end of the spindle. In the disk 37 is formed a centrally arranged opening 46 which is of the same diameter as the bore 17 in the shank. A bore 47 is formed in the hub portion 28 and extends from the lower end of said hub portion through the bottom wall of the cavity 24, which bore 65 has the same diameter as the bore 17 in the

shank and the opening 46 in the disk. At the lower end of said bore 47 is formed an inwardly extending annular shoulder 48, and in the side wall of the said bore is formed a longitudinally extending slot 49. An interiorly screw threaded sleeve 50 is arranged so as to fit closely in the said bores 17, 46 and 47 and yet be capable of sliding longitudinally through said bores. The said sleeve is made of such a length that in one extreme position thereof it will be entirely within the bore 47, but in its other extreme position a portion of said sleeve 50 will be in the bore 47 and the remainder of the sleeve will extend through the opening or bore 46 and into the bore 17. Therefore, when the sleeve 50 is in this position the blade carrying portion of the reamer and the shank portion are locked together so that neither can shift transversely of the other. That is, when the sleeve is in this position the floating of the blade carrying portion of the reamer is prevented. A screw 51 is inserted through the lower end of the bore 47 and the thread thereon is arranged to engage the interior screw thread of the sleeve 50. A pin 52 is secured in the sleeve 50 and extends into the slot 49. Now, when the screw 51 is turned in one direction the sleeve is drawn down into the bore 47 leaving the body or blade carrying portion free to float, and when the screw 51 is turned in the opposite direction the sleeve passes through the bore 46 and enters the bore 17 thereby positively preventing any movement of the blade carrying portion independent of the shank portion and bringing their axes into absolute alinement.

The arrangement for mounting and adjusting the blades in the blade carrying portion of the reamer is as follows:—In the body portion of the reamer are formed a plurality of peripheral radially arranged and longitudinally extending blade receiving slots 60, and toward the lower end of the body portion said slots extend completely through the wall of the cavity 26. The blades 61 are mounted in the said slots 60 so as to be snugly held therein and the lower rear portion of each blade extends through the slot and enters the said cavity 26. The blades are trapeziform, the outer or cutting edge of each blade being straight and extending parallel with the axis of the reamer, the base of the blade being arranged at a right angle to the cutting edge, the inner edge being inclined upwardly and the top edge being inclined outwardly and downwardly. At the inner edge of each blade is formed a notch 62, the side walls of said notch being inclined upwardly with respect to the base of the blade.

In the cavity 26 around the hub 28 is arranged an exteriorly screw-threaded sleeve 65 which is of equal length with the

said hub and is adapted to turn or revolve on said hub. Toward its outer end the interior diameter of said sleeve is increased forming an annular shoulder 66, and the exterior diameter is decreased forming a shoulder 67. A nut 68 is screwed onto the end of the hub and overlaps the shoulder 66 on the sleeve 65. Spanner holes 69 are formed in the exposed end of the sleeve 65 to permit the said sleeve's being engaged by a tool when it is desired to turn the said sleeve on the hub. On the sleeve 65 is arranged a screw threaded collar 70, the threads of which are arranged to engage the threads on the said sleeve 65. On the periphery of the said collar 70 are formed a series of outwardly projecting lugs 71 which are equal in number to the number of blade holding slots and are similarly spaced and are adapted to snugly fit into said slots. The said lugs are also arranged to fit into the notches 62 in the blades 61. The bottom edge of the said collar 70 is slightly beveled, as shown at 73. A ring 74 is screwed into the lower end of the body portion, and the inner side thereof overlaps the exterior shoulder 67 on the sleeve 65. The said ring 74 is provided at its upper end with a beveled seat 75 which corresponds to the bevel on the collar 70. Locking screws 76 are screwed into the said ring and the body portion which lock the ring against movement, and the lower ends of said screws also serve as bumpers to protect the lower ends of the blades. On the neck portion 23 is arranged a clamping ring 77 the lower edge of which is beveled and adapted to engage the top edge of the cutting blade, and the top edge is also beveled and is cut or notched, as at 79. Above the clamping ring 77 is arranged a lock ring 80 which is adapted to screw down on top of the clamping ring 78 and is interiorly beveled so as to engage the notched portion of the said clamping ring and squeeze the same tightly on the threads of the neck portion 23 to effectually lock the clamping ring against movement.

The operation of the reamer will be readily understood from the foregoing description. Assuming the various parts to be in the positions shown in Fig. 2, if it is desired to have the blade carrying portion free to float, the screw 52 is turned so as to draw the sleeve 50 down into the bore 47 and entirely out of the bore 17 and the opening 46 and the said sleeve will then be in the position shown in Fig. 3 and Fig. 5. Again, if we assume the blade are in the position shown in Fig. 2 and the other figures of the drawing and it is desired to adjust the blades so as to secure a deeper cut the lock ring 80 is screwed up on the neck 23 after which the clamping ring 78 is screwed up. The sleeve 65 is then engaged with a

spanner or similar tool and is rotated on the hub 28, and as the collar 70 is held against rotation owing to the lugs 71 thereon projecting into the blade holding slots 60 the said collar will move upwardly on 70 the sleeve 65, and as said collar moves upwardly the lugs 71 in engagement with the blades will carry the blades upwardly, and as the blades move upwardly they will also move outwardly owing to the inclined inner 75 edge of the blades and the inclined bottom wall of the blade holding slots. When the blades have been caused to project the proper distance the clamping ring 77 is screwed down on the upper ends of the 80 blades and the locking ring 80 is then screwed down on top of the clamping ring.

What I claim is:

1. An expansion reamer comprising a blade carrying portion, blades mounted in 85 said blade carrying portion and adjustable therein, said blade carrying portion being provided at its upper end with a circular cavity, a shank portion, a flange carried by said shank portion and adapted to be loosely 90 received within the cavity in the blade carrying portion, and means locking the flange to the said blade carrying portion while leaving it free to move transversely of the axis of the blade carrying portion. 95

2. An expansion reamer comprising a blade carrying portion, blades adjustably mounted in said blade carrying portion, said blade carrying portion having a cavity in its upper surface, a shank provided with a flange adapted to fit loosely within said cavity, a disk arranged in said cavity between the bottom surface of the shank and the bottom wall of the cavity, said disk being provided with two pairs of diametrically 100 arranged slots, a pair of diametrically arranged pins secured in the flange of the shank portion and arranged to extend into one pair of diametrically arranged slots in said disk and a pair of diametrically arranged pins secured in the bottom wall of the cavity of the blade carrying portion and arranged to extend into the other two diametrically arranged slots in said disk, said pins having a positive engagement with the side walls of said slots in said disk but having play between the inner end walls and the walls of the cavity in the blade carrying portion, and means for locking said flange in said cavity. 110

3. An expansion reamer comprising a blade carrying portion, blades adjustably mounted in said blade carrying portion, said blade carrying portion having a cavity at its upper end, a shank portion provided with a flange, arranged to fit loosely within said cavity, a disk arranged in said cavity between the lower end of the shank and the bottom wall of said cavity, said disk being 115 provided with slots which extend inwardly 120

- from the perimeter of said disk, said slots being arranged in pairs diametrically opposite each other, holes formed in the said disk intermediate of the first-mentioned slots, 5 balls arranged in said holes, the diameter of said balls being slightly in excess of the thickness of said disk, pins secured in the flange of the shank portion and adapted to extend down into one pair of diametrically arranged 10 slots, balls arranged in said disk, pins secured in the bottom wall of the cavity of the blade carrying portion and adapted to extend into the other pair of said diametrically arranged slots, rollers mounted in the sides of said 15 pins within said slots and a ring mounted on the shank portion and arranged to screw into the upper end of the body portion to prevent the outward movement of the shank portion.
- 20 4. An expansion reamer comprising a blade carrying portion having a cavity at its upper end, blades adjustably mounted in said blade carrying portion, a bore extending from the bottom surface of the blade carrying portion centrally therethrough, a disk arranged in the cavity of the body portion, said disk having a central opening in line with the bore in the body portion, a shank portion adapted to extend down into 25 said cavity in the blade carrying portion, said shank portion being provided with a bore in line with the bore in the blade carrying portion, means for forming an operative connection between said shank portion and the said disk and said disk and said blade carrying portion permitting said blade carrying portion to float on the shank portion, a sleeve mounted within the bore of the body portion and adapted to slide freely therein, 30 and in its locking position extend through the opening in said disk and into the bore in the shank portion, said sleeve being provided with interior screw threads, means for preventing the rotation of said sleeve and a screw mounted in the blade carrying portion and extending into the said sleeve and engaging the thread thereon.
- 35 5. An expansion reamer comprising a blade carrying portion, a shank portion connected with the blade carrying portion, said blade carrying portion having a cavity extending upwardly from the bottom surface thereof, said cavity being annular in cross section and the blade carrying portion extending down centrally of said cavity and forming a hub, said blade carrying portion having slots formed in the peripheral wall thereof, the bottom wall of said slots being inclined to the axis of the blade carrying portion, and at the lower end of the body portion said slots extending completely through the body portion, blades mounted in said slots, the inner edge of each blade being inclined corresponding to the inclination of the bottom walls of said slots and each blade being 40 also provided with a notch which extends inwardly from the inner edge of the blade, a ring arranged around the hub portion of the blade carrying portion, means for locking said ring against longitudinal displacement 70 while leaving it free to turn on said hub, said ring being provided with an exterior screw thread, a screw threaded collar arranged on said ring, said collar being provided with lugs which extend into the blade carrying slots and also into the notches in the said blades and a clamping ring secured above said blades and engaging the upper end of said blades.
- 45 6. An expansion reamer comprising a blade carrying portion consisting of a neck portion and a body portion, the neck portion being provided with an exterior screw thread and having a cavity extending down from the upper surface thereof and the body portion having a cavity extending upwardly from the bottom surface thereof, the body portion extending down centrally of said cavity in the form of a hub, said body portion also being provided with radially arranged blade receiving slots, the bottom walls of which are inclined at an angle to the axis of the reamer, blades arranged in said blade carrying slots, the inner edges of said blades being inclined corresponding to the 80 inclination of the bottom of said slots, but the upper edges of said blades being beveled, a beveled clamping ring arranged on the neck portion and adapted to engage the upper ends of said blades, a locking ring arranged above the clamping ring, an exterior screw threaded sleeve arranged on the hub portion of the body portion, and a screw threaded collar arranged on said sleeve and provided with lugs which extend into the 85 blade carrying slots and the notches in said blades.
- 50 7. An expansion reamer comprising a blade carrying portion and a shank portion, means for securing the shank portion to the body portion so as to permit of the body portion moving transversely of the axis of the shank portion, a cavity formed in the bottom of the body portion, a hub portion extending down centrally of said cavity, said body portion being provided with radially arranged blade receiving slots which extend partially through said body portion, the bottom walls of said slots being inclined to the axis of the reamer, blades arranged in the blade carrying slots, the inner edges of said blades being inclined corresponding to the inclination of the bottom of the slots and having notches extending inwardly therefrom, a sleeve arranged around the hub, said sleeve being provided with an exterior screw thread, a collar arranged on said sleeve, said collar being provided with lugs which extend into the blade carrying slots and the notches in said blades, a ring arranged to screw into the bot- 90

tom of the body portion for holding said sleeve against longitudinal movement and locking rings mounted on the upper end of the body portion for holding the clamping 5 ring against movement.

8. An expansion reamer comprising a blade carrying portion and a shank portion, the blade carrying portion being provided with a cavity adapted to receive the lower 10 end of the shank portion and loosely engage the same, means operatively connecting the shank portion with said blade carrying portion so that said blade carrying portion will turn with the shank portion while leaving it 15 free to float on the shank portion, said blade carrying portion having an annular cavity formed in the bottom thereof, radially arranged blade receiving slots formed in the blade carrying portion, the bottoms of said

slots being inclined and at their lower ends 20 communicating with said cavity, a sleeve arranged around the central part of the blade carrying portion, a collar mounted on said sleeve, said collar having lugs adapted to engage with the blades in the blade receiving 25 slots and a ring arranged to screw into the lower end of the blade carrying portion and engage said sleeve, said ring having slots corresponding to the slots in the blade carrying portion and adapted to receive the lower 30 portions of the blades.

In testimony whereof, I sign the foregoing specification, in the presence of two witnesses.

DELANO H. DUGAR.
